UNITED STATES PATENT OFFICE.

EDWIN F. BRITTON, JR., OF MAPLEWOOD, NEW JERSEY, ASSIGNOR TO MONROE CALCULATING MACHINE COMPANY, OF NEW YORK, N. Y., A CORPORATION OF NEW YORK.

SHOCK-ABSORBER FOR CALCULATING-MACHINE CARRIAGES.

1,384,592.

Specification of Letters Patent. Patented July 12, 1921.

Application filed April 14, 1920. Serial No. 373,835.

To all whom it may concern:

Be it known that I, EDWIN F. BRITTON, Jr., a citizen of the United States, resident of Maplewood, in the county of Essex and State of New Jersey, have made a certain new and useful Invention in Shock-Absorbers for Calculating-Machine Carriages; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a front view of a machine embodying the invention, with parts broken away and parts in section. Fig. 2 is a section on the line 2—2, Fig. 1. Fig. 3 is a section of the left hand end of the machine, on the line 3—3, Fig. 2, with the carriage raised. Fig. 4 is a section of the rear portion of the machine on the line 4—4, Fig. 1, with the carriage raised.

The invention has relation to shock absorbers, and more particularly to cushioning means for the endwise-shiftable carriages of calculating machines or registers, such for instance as disclosed in the reissue patent to Baldwin, No. 13,842, an object being to facilitate the shifting of the carriage and to lessen the jar or shock consequent upon the fall of the carriage in shifting the same.

The invention consists in the novel construction and combinations of parts, as hereinafter set forth.

In the accompanying drawings, illustrating the invention, the numeral 1 designates the casing of a calculating machine of the type of the patent stated, and 2 is the endwise-shiftable carriage, pivoted in rear to said casing at 59. Intermediate gears 12, mounted upon a shaft of the main frame 1, are adapted to mesh with the gears 13' of register wheels 13, the latter mounted upon a shaft having support in the carriage. The intermediate gears 12 are rotated by primary selecting elements 5, mounted upon shaft 4, and by carry members 7, upon shaft 73, the shafts 4 and 73 being rotated by suitable driving connections to operate the wheels 13 and register thereon the amounts set up on the keyboard 18, all as described in said patent.

The carriage 2 is shifted endwise by means

of a rotatable rod 61, crank pins 64 of said rod engaging notches 7 of the lower forward edge of the carriage in the shifting operation, the carriage being raised pivotally as it is shifted, in order to disengage the gears of the register wheels from the intermediate gears 12, also as described in said patent.

The rod 61 being operated to raise the carriage pivotally and effect the first half of the shifting operation, and the crank pin 64 having passed dead center, the latter half of the shifting operation will be accomplished automatically, through force of gravity, as stated particularly in said patent.

Means are provided to draw the carriage 70 positively downwardly and to positively engage the gears of the register wheels fully with the intermediate gears upon the initial movement of the operating device or crank handle 3 of the machine, or before any rotation of the wheels 13 can occur in registering, as described particularly in a co-pending application for patent of E. E. Phinney, S. No. 356,882.

This means comprises a disk 4, fast upon the selector shaft 4 and having a circumferential notch 5, a compound lever 6 being pivoted at 7 and having a toothed extension 8, normally underlying said notch, and an extension arm 9, pivoted to the main lever 6 at 10 and having an upper hooked end 11, engaging a horizontal ledge or shoulder 12, at the forward lower portion of the carriage.

In the normal position of the parts stated, the carriage is capable of being raised pivotally, the compound lever 6 being raised therewith and the tooth 8 of said lever entering the notch 5 of the disk. In the latter half of the shifting operation, or in the fall of the carriage to normal or lower position, should the downward movement of the carriage be incomplete, or such as not to fully engage the gears of the register wheels with the intermediate gears, no harm will be done, inasmuch as the initial movement of the crank handle in the registering operation will rotate the shaft 4 and thereby cause one or the other of the end walls of the notch 5 to engage the tooth 8 and force the lever 6 downwardly, thereby bringing the gears of the registering wheels fully into mesh with the intermediate gears prior to any rotation of the intermediate gears in registering.

At the right-hand end of the casing, a lever 20 is fulcrumed intermediately of its

length at 20', said lever having, at the upper end of its upper arm, an anti-friction roller 21, located immediately below the lower forward horizontal edge portion 22 of the carriage shell, just in rear of the ledge *h* aforesaid, being held upwardly against said edge by a spring 23 connected with the lower arm of the lever.

As the carriage is raised pivotally, the 10 spring 23 will actuate the lever, and the anti-friction roller 21 will follow the carriage upwardly, in constant engagement with the lower forward edge of the carriage shell, and upon release of the carriage, or in the 15 latter half of the shifting operation, the fall of the carriage will be resisted by the spring pressure of said roller sufficiently to cause the carriage notch *i* coming into action to engage the related crank pin 64 in a cushioned manner, or without shock or concussion.

The spring 23 being of sufficient strength to properly cushion the carriage in its fall, would ordinarily, or without the coaction 25 of the carriage locking or positioning means stated, tend to hold the carriage sufficiently raised at all times to disengage the gears of the registered wheels from the intermediate gears, or at least to hold these gears 30 from fully meshed engagement. The spring 23 is therefore enabled to be made of sufficient strength to counteract a considerable proportion of the weight of the carriage, the allowance of a considerable factor of 35 safety being unnecessary, owing to the coaction of the carriage locking and positioning means stated, since, should the spring interfere with the proper meshing of the gears, the carriage locking and positioning 40 means would correct this before any registration could take place.

It has previously been necessary to provide means on the frame of the machine, engaged by means on the carriage shell, to 45 limit the downward movement or fall of the carriage, but in view of the cushioning device active throughout the fall of the carriage to gradually bring it to rest, the aforesaid stop or limiting means is enabled to 50 be eliminated, and the carriage limited in its downward movement by engagement of the notches at the forward edge of the carriage shell with the crank pins 64, no shock or vibration being transmitted to the carriage shifting rod.

The invention is found to eliminate the objectionable noise and shock or vibration consequent upon the shifting of the carriage, and has the further advantage of 60 lightening the resistance to be overcome, whereby the shifting operation is facilitated.

I claim:

1. In a calculating machine having a 65 series of gears, an endwise-shiftable pivoted

carriage having register wheels, a series of gears connected therewith and engaging the first-named gears, and means engaging the carriage to raise the same pivotally and shift it endwise, means for cushioning the 70 fall of the carriage active throughout the fall thereof.

2. In a calculating machine having a series of gears, an endwise-shiftable pivoted carriage having a series of gears engaging the first-named gears, and means engaging the carriage to raise the same pivotally and shift it endwise, means for cushioning the 75 fall of the carriage active throughout the fall thereof, and means for insuring the full engagement of said gears as stated.

3. In a calculating machine, a series of gear wheels, an endwise-shiftable pivoted carriage having a series of gear wheels engaging the first-named gear wheels, means 85 for operating said gear wheels, and means for raising the carriage pivotally and shifting it endwise, means for cushioning the fall of the carriage active throughout the fall thereof, and means actuated by said 90 operating means to insure the engagement of said gears as stated.

4. In a calculating machine, a series of gear wheels, an endwise-shiftable pivoted carriage having a series of gear wheels engaging the first-named gear wheels, means for operating said gear wheels, and means for raising the carriage pivotally and shifting it endwise, means for cushioning the fall of the carriage active throughout the 100 fall thereof, and means for insuring the engagement of said gear wheels during the operation thereof.

5. In a calculating machine, a series of gear wheels, an endwise-shiftable pivoted carriage having a series of gear wheels engaging the first-named gear wheels, and means for raising the carriage pivotally and shifting it endwise, means for cushioning the fall of the carriage active throughout the fall thereof and consisting of a spring-pressed lever engaging the free edge 110 portion of the carriage.

6. In a calculating machine, a series of gear wheels, an endwise-shiftable pivoted carriage having a series of gear wheels engaging the first-named gear wheels, and means engaging the carriage to raise the same pivotally and shift it endwise, of means for cushioning the fall of the carriage, normally tending to raise the carriage pivotally, and means for forcing the carriage downwardly and insuring full engagement of the gear wheels.

7. In a calculating machine, a series of gear wheels, an endwise-shiftable pivoted carriage having register wheels, a series of gear wheels connected therewith and engaging the first-named gear wheels, means 125 engaging the carriage to raise the same piv- 130

totally and shift it endwise, selecting elements, carry mechanism, and an operating device for said selecting elements and carry mechanism, means for cushioning the fall 5 of the carriage normally tending to raise the carriage pivotally, and means for forcing the carriage downwardly and insuring full engagement of the gear wheels, operative upon the initial movement of said operating device.

8. In a calculating machine, a series of gear wheels, an endwise-shiftable pivoted carriage having a series of gear wheels engaging the first-named gear wheels, and 15 means engaging the carriage to raise the same pivotally and shift it endwise, means for cushioning the fall of the carriage normally tending to raise the carriage pivotally, and means for forcing the carriage 20 downwardly and insuring the engagement of said gear wheels, the carriage shifting means being adapted to limit the downward movement of the carriage.

9. In a calculating machine, a series of 25 gear wheels, an endwise-shiftable pivoted

carriage having a series of notches and a series of gear wheels engaging the first-named gear wheels, means for raising the carriage pivotally and shifting it endwise, including a rotatable rod having a double 30 crank arm provided with pins engaging said notches, selecting elements, carry mechanism, and an operating device for said selecting elements and said carry mechanism, means for cushioning the fall of the carriage normally tensioned to raise the carriage pivotally, and means for forcing the carriage downwardly to insure full engagement of the gears, operative upon the initial movement of said operating device, said 35 crank pins being adapted to engage said notches to limit the downward movement of the carriage.

In testimony whereof I affix my signature in presence of two witnesses.
